UNITED STATES PATENT OFFICE.

GEORGE H. DAWSON, OF CAMBRIDGE, MASSACHUSETTS, ASSIGNOR TO LIBRARY
BUREAU, A CORPORATION OF NEW JERSEY.

INDEX-CARD SUPPORT.

Application filed December 5, 1921. Serial No. 530,185.

To all whom it may concern:

Be it known that I, GEORGE H. DAWSON, a citizen of the United States, and a resident of the city of Cambridge, in the county of Middlesex and State of Massachusetts, have invented certain new and useful Improvements in an Index-Card Support; and I do hereby declare that the following is a full, clear, and exact description of the same, reference being had to the accompanying drawings, and to the numerals of reference marked thereon, which form a part of this specification.

This invention relates to visible index cards which are removably mounted in a tray in overlapping relation with their lower edges exposed, and this invention concerns itself primarily with the supporting means upon which the cards are removably mounted.

My invention comprises the novel structure, mechanisms and arrangement herein-after described and more particularly pointed out and defined in the appended claims.

In the accompanying drawings which illustrate certain preferred embodiments of my invention and in which similar reference numerals refer to similar features:

Figure 1 is a fragmentary front plan view of a tray illustrating the cards mounted therein in overlapping relation with the lower edges exposed.

Figure 2 is an enlarged front plan view of a card mounted on its support ready for insertion in the tray.

Figure 3 is an edge view of Figure 2 upon an enlarged scale.

Figure 4 is an enlarged transverse section through the tray.

Figure 5 is a fragmentary perspective enlarged view of a metal clip used.

Figure 6 is an enlarged edge view of a fabric hinge forming part of the card support.

Figure 7 is a fragmentary enlarged view of a modified form of spacing and supporting bar.

Figure 8 is a fragmentary enlarged view of another modified form of supporting and spacing bar.

In referring to the drawings, it will be observed that the cards 1 are mounted upon fabric hinges 2 connected to spacing bars

3 of rectangular formation which slidably fit in guide channels 4 formed by the bent-over edges 5 of the tray. When a plurality of cards are thusly supported in a tray, they will overlap a distance equal to the width or height of the spacing bars as is well-known in the art.

My invention relates primarily to the supporting means for the cards and comprises the fabric hinge 2 which is preferably sized in order to impart sufficient rigidity thereto and stamped or pressed or creased into a card-attaching portion 6, a hinge portion 7, and a bar-attaching portion 8 (Figure 6), the card-attaching portion 6 being provided with lateral flaps 9 which are bent inwardly so as to overlap a portion of the front face to which they are secured by studs or eyelets 10 so that a notched card can readily be inserted thereunder for the purpose of engaging the studs or eyelets. The bar-attaching portion 8 is designed to be folded over the top of the bar 3 and down the opposite side to some extent and firmly secured thereon by a metal clamp 11. The metal clamp 11 is originally of U-shape having flanges of unequal length, one flange being substantially shorter than the height, the distance from the top to the bottom of the bar 3, while the other flange being a trifle longer than the height of the bar. In attaching the metal clamp, it is placed over the fabric, folded partially around the bar with the longer flange on the rear side; the portion of the longer flange projecting below the bottom of the bar 3 will then be crimped over the bottom thereof as indicated at 11^a in Fig. 3, firmly securing the clamp to the bar against relative movement thereof, thus preventing the fabric from being removed from or shifted on the bar.

The shorter flange is adapted to extend only to the top of the inclined hinge portion 7 so that the card will have a tendency to hang beyond the plane of the front face of the bar. The permanently combined hinge member 2 and bar thus produce a very simple and efficient card support.

The index card 1 is provided with a novel lateral notch 1 or recess in each side adjacent the top (Figure 1), the bottom of the notches being spaced apart a distance equal to the distance between the studs 10;

and the card is adapted to be mounted or removed by flexing the same sufficiently so that it can pass between the studs 10. When the card 1 is in mounted position upon its support, the flaps 9 will bear against the front face of the card and prevent lateral movement thereof as is obvious.

Instead of using a metal clamp to attach the hinge to the bar 3, the bar may be provided with a clamp slot 12 as shown in Figure 7 in which the upper margin of the hinge member may be securely and firmly clamped.

In some cases, a light channel-shaped bar 15 made of folded metal may be used to advantage for supporting and spacing the cards. In Figure 8, I have illustrated such a channel bar in which a sheet of metal is folded into channel-shape with the terminal margins 13 and 14 overlapping on the rear side of the web. The fabric hinge is adapted to be suspended from the upwardly extending margin 14 by a portion folded thereover and the marginal terminal 13 is adapted to be pressed or jammed against the web of the channel so as to permanently anchor the hinge member in place.

It is characteristic of my invention that the upper margin of the hinge member is 30 permanently clamped or secured to a substantially rigid bar whereby the device may be secured in a tray. In the constructions illustrated, the margins of the hinge members are infolded in or about the bar, and the hinge projects from the front face of the bar that forms a lateral support therefor, but any means may be used for permanently securing the hinge member of the bar.

I am aware that numerous details of con-

struction may be varied through a wide range without departing from the principles of this invention, and I therefore do not purpose limiting the patent granted otherwise than necessitated by the prior art.

I claim as my invention:

45

1. In a card index system, a sized fabric hinge member having a card-attaching portion, a hinge portion extending at an angle to said card-attaching portion, and a bar-attaching portion extending at an angle to 50 said hinge portion.

2. A hinged card support embracing a fabric strip, and means adjacent each end thereof adapted to engage the notched edges of a card for supporting the same, a substantially 55 rigid bar, and means permanently gripping the margin of the hinge member to said bar.

3. In a card index system, the combination with a supporting and spacing bar, of a fabric hinge having its upper margin folded 60 over said bar, and a metallic clamp embracing said hinge and bar and embracing the sides and top of the latter with one margin crimped over the bottom thereof.

4. In a card index system, a supporting 65 bar, a fabric hinge member, and means associated with said bar for clamping the upper end of said hinge member thereto, said hinge member being creased upon a line contiguous to a lateral face of said bar and extending at an angle thereto.

In testimony whereof I have hereunto subscribed my name in the presence of two subscribing witnesses.

GEORGE H. DAWSON.
